VALVE SPRING COMPRESSOR

Filed Oct. 1, 1931

FIG-4

11 R. B. LAW
INVENTOR.
5 BY
Merrill M. Blackburn
ATTORNEY

UNITED STATES PATENT OFFICE

RAY BRADLEY LAW, OF MUSCATINE, IOWA

VALVE SPRING COMPRESSOR

Application filed October 1, 1931. Serial No. 566,195.

The present invention relates to a device for compressing springs and, while the same is designed primarily for use in connection with actuating springs for the valves of automobile tractor or truck engines, it will be understood that the same is useful for other purposes as well and it is therefore not intended to be restricted to any specific use.

Among the objects of this invention are to make a device of the character indicated which may be easily operated with a single hand; to provide a device which will automatically lock the parts in any desired position; to provide a device of the character indicated which can easily be unlocked and released from movement in a direction opposite to the compressing movement; to provide a device of the character indicated which cannot lock in such a manner that it cannot be actuated so as to be unlocked; to provide a simple, easily adjustable device capable of being used upon any style of automobile, regardless of the natural obstructions which may exist within the hood of the car; to provide a device of the character indicated having a wide range of adjustment; to provide a device of the character indicated whose operation is not affected by the presence of grease or oil; and such further objects, advantages and capabilities as will hereafter appear and as are inherent in the construction disclosed herein. My invention further resides in the combination, construction and arrangement of parts illustrated in the accompanying drawing and, while I have shown therein what is now considered the preferred embodiment of this device, I desire it understood that various modifications are contemplated and are believed to be within the scope of this invention.

In the drawing annexed hereto and forming a part hereof,

Fig. 1 is an elevation of a device embodying this invention;

Fig. 2 is a plan view of the structure shown in Fig. 1;

Fig. 3 is a fragmentary elevation of a portion of the structure shown in Fig. 1, with certain parts shown in a different position of adjustment;

Fig. 4 is an elevation of an element of the present construction;

Fig. 5 is a transverse section taken substantially along the plane indicated by the line 5—5, Fig. 1;

Fig. 6 is an elevation of a part of the locking mechanism;

Fig. 7 is a fragmentary view of a portion of the structure shown in Fig. 1, with the parts shown in different positions of adjustment and illustrating this device used as a means for compressing springs preparatory to inserting them into an automobile engine;

Fig. 8 is a longitudinal section taken substantially along the plane indicated by the line 8—8, Fig. 1.

Reference will now be made in greater detail to the annexed drawing which illustrates a generally U-shaped frame 1 having at the end of one arm a pair of jaws 2 or 2a designed to receive one end of a valve spring, preparatory to compressing the same. Mounted upon the end of the other arm of the frame is a head 3 which is longitudinally apertured for the reception of a plunger 4 which is more or less pointed, as indicated at 5, to engage a depression in the end of a valve and which has a transverse opening adjacent its opposite end for the reception of a pin 6. The purpose of this will be referred to in greater detail hereinafter.

A collar 7 surrounds the plunger 4 and is adjustable with relation thereto merely by loosening the screw 8 which passes through the collar 7 and engages the side of the plunger 4. This bolt or screw 8 is provided with a head 9. This head may be hexagonal in form and may have a handle 10 passed through an opening therein to serve as an operating handle whereby the bolt may be turned.

On the other hand, the handle 10 may be entirely omitted and the bolt may be turned by means of a wrench applied to the head 9. I prefer the latter construction, in which the handle 10 is omitted.

A pair of links 11 are connected to the collar 7, one by the bolt 8 and the other by a corresponding bolt 12. The opposite ends of these links 11 are connected to the arms

of a split lever 13, as indicated at 14. The lever 13 is mounted upon a pivot 15, passing through the lever 13 and a bracket 16 which connects the head 3 with the upper arm of the frame 1.

A plurality of members 18, pivoted at 19 on the upper arm of the frame, are provided with arcuate slots 20 through which passes a bolt 21, which bolt also passes through an elongated opening 22 in the head 23 of a latching member. As indicated in Fig. 2, this head is wedge shaped and is biased toward locking position by means of the spring 24 surrounding the shank 25 of the latching member. The shank 25 is pivotally connected to the angular lever 26 by means of which the latching member is drawn back, the spring 24 being compressed. A link 28 is mounted upon the pivot member 15 and bolt 21 and is located between the arms of the lever 13. An enlargement upon the link 28, a tapered washer, or other equivalent means surrounds the bolt 21 and is arranged to cooperate with the tapered or wedge shaped head 23 of the latching member. It will therefore be apparent that when the lever 26 is released the spring 24 will force the wedge shaped head 23 to press the links 18 outwardly against the arms of the lever 13. Fiber or other suitable washers surround the bolt 21 and are located between the links 18 and between one of these and member 28. Therefore, members 18 and lever 13 are prevented from having movement relative to each other when head 23 is pushed forwardly by spring 24. Thus, lever 13 is locked in any adjusted position and holds the plunger 4 where it may happen to be.

By pressing lever 26 toward the end 30 of lever 13 and then raising this lever, the plunger 4 is forced downwardly or, rather, the lower arm of frame 1 is raised, causing compression of spring 31, shown in dotted outline in Figs. 1 and 7. When proper compression is reached, the handle 26 is released and the head 23 is forced inwardly to cause the latching or grasping of the device and the holding of spring 31 compressed.

The frame 1 may be made integral, if desired, or, if preferred, it may be made in two sections provided with slots 32 through which pass the bolts 33 which are threaded into one of these members so as to permit relative sliding of one relative to the other. When proper adjustment of these parts is secured, the bolts 33 are turned in so as to tightly hold these two parts of the frame, relatively to each other.

Adjustment of the distance between the end 5 of plunger 4 and the spring holder 2 may be accomplished in other ways than by sliding the two arms of the frame 1 relative to each other. As a matter of fact, the slots 32 and bolts 33 may be dispensed with en-

tirely, if desired. One of the means for making the adjustments referred to is the screw 8 which may be turned out so that it does not engage the plunger 4 and this plunger may then be adjusted longitudinally through the head 3 and collar 7, whereupon the screw or bolt 8 will again be turned in to secure the plunger 4 against movement relative to the collar 7. It will therefore be seen from this that a considerable range of adjustment may be had in this way. Also, a different range of adjustment may be had by reversing the links 11 and placing the collar 7 on the upper portion of the plunger 4, as illustrated in Fig. 3. The two arrangements can be compared by comparing Figs. 1 and 3 which show same. Fig. 7 shows the relative arrangement of the parts when the handle 30 is raised and the plunger 4 depressed, the collar 7 being below the head 3, as in Fig. 1.

Fig. 7 also illustrates the use of this device in compressing a spring preparatory to installing same in an automobile. To accomplish this, the parts of the device are arranged as in Fig. 1 and the pin 6 is removed from the plunger 4. A spring 31 is then mounted upon the upper end of the plunger 4 and the pin 6 is replaced as illustrated. The handle may now be raised and this will cause longitudinal motion of the plunger 4 and compression of the spring 31, as indicated in Fig. 7. A spring holder may then be placed about the spring 31 to hold the same compressed. If the lever 13 is now lowered, it causes the plunger to be raised toward the position shown in Fig. 1 and the pin 6 may be withdrawn, thus permitting the spring to be removed from the plunger 4 and inserted in its normal place in the engine.

The action of the clutch may be varied by tightening or loosening the nut of the bolt 21 which draws the parts closer together or permits them to spring farther apart. It will therefore be evident that when such an adjustment is made the latching means will be effective sooner or later, depending upon the direction of adjustment of said nut. It will be apparent that it is not necessary to press the handle 26 down fully so as to completely release the latching or gripping means and that if this is only partially released, the plunger 4 and jaws 2 will approach as slowly as may be desired, the speed being regulated by the pressure upon lever 26.

It is of course understood that the specific description of structure set forth above may be departed from without departing from the spirit of this invention as set forth in this specification and the appended claims.

Having now described my invention, I claim:

1. In a valve spring compressor, a frame having a head extending transversely to one side of the frame and in the plane thereof,

said head being apertured longitudinally for the reception of a plunger, a plunger reciprocably mounted in the aperture of the head, means for reciprocating the plunger in the aperture including as a part thereof a lever mounted upon the frame, and frictional holding means capable of holding the lever in any position of adjustment thereof.

2. In a valve spring compressor, a frame, 10 a plunger mounted for reciprocation therein, a lever for reciprocating said plunger, and holding means for holding the lever in various positions of adjustment, said holding means comprising an elongated, flat, longitudinally slotted member carried by the frame, an engaging element carried by the lever and adapted to cause frictional gripping of the slotted member at any point desired, and resilient means to actuate the holding element into position to cause such gripping.

3. A structure for the purpose indicated comprising a frame having an arm carrying a longitudinally apertured head, a plunger 25 slidable in the aperture in said head, a lever pivotally mounted on said frame and connected to said plunger to slide same through said aperture, a laminated slotted link connected to said frame and said lever, means on 30 said lever for immovably connecting the lever to the link so that the plunger will be held against sliding in said aperture, and non-metallic friction means between the lever and the slotted link to enable the operator to slowly release spring tension.

4. In a structure for the purpose indicated, a frame comprising a head having a plunger 40 slidable therethrough, a slotted holding member pivotally connected to the frame, a lever pivotally connected to the frame and connected to the plunger to cause actuation thereof through the frame, and clamping means carried by the lever and frictionally engageable with the slotted holding member, with 45 varying degrees of pressure, to measurably retard the movement of the lever and plunger, said clamping means serving to hold the lever and plunger in any desired position of adjustment.

5. In witness whereof, I hereunto subscribe my name to this specification.

RAY BRADLEY LAW.
